UNITED STATES PATENT OFFICE.

WILLARD E. BROWN, OF PHILADELPHIA, PENNSYLVANIA.

PLOW.

SPECIFICATION forming part of Letters Patent No. 310,249, dated January 6, 1885.

Application filed September 5, 1884. (No model.)

To all whom it may concern:

Be it known that I, WILLARD E. BROWN, a citizen of the United States, residing at Philadelphia, in the county of Philadelphia and State of Pennsylvania, have invented certain new and useful Improvements in Plows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention has relation to plows intended for use in thick waxy soil, such as is usually found in the prairies of the West; and it has for its object to provide efficient means by which to lubricate the polished surface of the 20 mold-board in order that the soil will not stick thereon and impede the motion of the plow.

In the drawings, Figure 1 is a side view of the mold-board side of my share attached to a standard and beam. Fig. 2 is an elevation 25 of the inner side of the mold-board. Fig. 3 is a transverse section of the mold-board on line $x-x$, Fig. 2. Fig. 4 is a longitudinal section of the mold-board on line $y-y$, Fig. 2, all of which will be described.

30 The mold-board A may be of any desired shape, and is by preference made of steel with a highly-polished surface. In the back of this mold-board I form the chamber B, about co-extensive with the surface of said mold-board, 35 as shown. I prefer to form this chamber by means of a plate, C, secured at its edges by rivets, or in other suitable manner, to the mold-board. This plate C is provided with an opening, C', which is arranged, by preference, at about the middle of said plate, and 40 communicates, therefore, with the chamber B at the middle portion of the latter. In operation I close this opening by a cover, D, sliding in guide C², formed on the opposite edges 45 of the opening C'. I fill the chamber B with packing E, of cotton-waste or other like substance suitable to carry oils. This packing may be placed in and removed from the chamber through opening C, and by the central arrangement of said opening I am able to con-

veniently and equally spread the packing in the chamber B. In practice I thoroughly saturate this packing with oil. This may be done before it is put in the chamber, or by turning it down on its side to the position in which Fig. 4 is shown and pouring the oil through the opening C. This oil is passed through openings a through the mold-board, and is distributed over the surface thereof, lubricating it and preventing the clays from sticking. The 55 shape and arrangement of these openings form an important feature of my invention. It will be noticed from Fig. 1 that the openings a are elongated transversely the direction of the mold-board, and are arranged in rows A', the 60 openings of each row being arranged in line with each other, and the said rows being parallel to each other, as shown in the said Fig. 1. By this formation and the arrangement of the openings a of each row close together I 65 form almost continuous slots through the mold-board transverse the direction of the plow, and the oil passes through the openings a , and is distributed over the surface of the mold-board 70 between each row A' and the row next in rear, 75 thus accomplishing a thorough oiling of the surface of the mold-board.

It is manifest that instead of a steel mold-board a wooden one might be used; but such would absorb and hold as much, if not greatly 80 more, oil than would be distributed on its surface, and I prefer to use the steel or other metallic surface, because by same I secure the application and use of the entire quantity of oil for the desired purpose and prevent waste. 85

Heretofore plow mold-boards have been perforated, and provided with chambers arranged on their rear side, into which oil has been poured, so it might flow through the perforations in the mold-board. Air and water have 95 also been forced into such chambers, and the perforations in the mold-board have been formed of slots elongated transversely to the line of motion of the plow, and arranged in a single row. These, broadly, are not my in- 100

vention. By their use the oil flows out freely, and is used in great excess of the necessity, resulting in so considerable an expenditure for oil as to render the constructions above described impracticable in most instances.

My invention differs most essentially from the constructions referred to by the use of packing as a carrier for the oil, so that the same may gradually ooze off through the openings in such degree as will give good and the desired results, and yet will not flow out of said openings in a stream, as would be the case were the packing omitted.

My invention also differs from the constructions before referred to in the arrangement of the opening C' into chamber B, so the packing may be conveniently distributed through said opening. I do not therefore claim, broadly, a perforated mold-board, nor a mold-board having slots formed through it elongated transversely to the direction of motion and arranged in a single row, nor yet a perforated mold-board having on its rear side a chamber adapted to receive oil; but,

Having thus described my invention, what I claim, and desire to secure by Letters Patent, is—

1. A mold-board having perforations or openings formed through it, and formed with

a chamber, B, on its rear side, and packing 30 placed in said chamber, and adapted to carry oil and deposit same through the openings in the mold-board, substantially as set forth.

2. In a plow, the mold-board of metal, having a polished surface and openings formed 35 through it, and provided in its rear side with a chamber, B, and packing held in said chamber and saturated with oil, substantially as set forth.

3. The improved mold-board made of metal, 40 and provided with openings *a*, elongated transversely the direction of the length of the mold-board, and arranged in parallel rows A', and provided on its rear side with chamber B, having 45 centrally disposed opening C', having guides C² C² on its opposite edges, the packing held in chamber B, and the door or cover D, sliding in guides C², and adapted to close opening C', substantially as set forth.

In testimony whereof I affix my signature in 50 presence of two witnesses.

WILLARD E. BROWN.
